UNITED STATES PATENT OFFICE.

WARREN WARNER, OF CINCINNATI, OHIO.

PISTON.

SPECIFICATION forming part of Letters Patent No. 234,374, dated November 9, 1880.

Application filed June 21, 1880. (No model.)

To all whom it may concern:

Be it known that I, WARREN WARNER, of Cincinnati, Hamilton county, Ohio, have invented certain new and useful Improvements 5 in Pistons, of which the following is a specification.

This invention relates to those pistons whose elastic packing-rings are forced outwardly by the pressure of water or steam, or other medium 10 employed for driving the engine or motor; and my improvement comprises a novel combination of head, follower, packing-ring, and gaskets, whereby such a piston is rendered especially applicable to hydraulic elevators, the 15 details of this construction being hereinafter fully described, and pointed out in the claims.

In the annexed drawings, Figure 1 is an axial section of the form of my piston adapted for use with a hydraulic elevator that operates 20 with a pulling force. Fig. 2 is an axial section of the component members of the piston detached from each other. Fig. 3 is an axial section of the form of my piston adapted for use with a hydraulic elevator that operates 25 with a pushing force. Fig. 4 is a plan of the head of the latter form of the device, the follower of the same being removed; and Fig. 5 is an enlarged sectional view of a modification of the invention.

30 A represents a portion of the cylinder of the hydraulic elevator or other water-motor, and B is the piston-rod of the same, said rod being secured in any approved manner to the head C, which latter, as represented in Figs. 1 and 2, 35 is provided with an annular flange, D, tapped at d to receive the bolts E, wherewith the follower F is secured to the piston. Furthermore, this head has a circular series of holes, c, whose duty will presently appear.

40 The follower F, just referred to, is preferably annular, and when secured in position clamps a gasket, G, between it and the face of flange D. H is another gasket, resting against the head C, and extending from the 45 margin of the same to the outer periphery of flange D, said gasket having perforations h in line with the holes c. Located between these 50 two gaskets is the packing-ring I, which may be a complete annulus, or it may be composed of a number of sections or segments. Furthermore, this ring and the gaskets G H are

made of leather or india-rubber, or other fibrous or non-metallic material, as the use of metal at this part of the piston would render the latter unfit for hydraulic purposes.

When the water is exerting its force in the direction of the arrow seen in Fig. 1, it is evident the fluid enters the apertures c h, thereby filling the annular chamber between the flange D and ring I, and consequently the latter is 60 expanded in exact proportion to the pressure in cylinder A. In this respect my device is not materially different from other steam or water-packed pistons; but the interposition of the gaskets G and H renders said device much 65 more sensitive, and thus insures a more reliable joint. If the ring I were clamped directly between the metallic head C and follower F, said ring would soon become so firmly attached to these two members as to resist any action 70 of the water, and consequently it would not be expanded so as to singly fill the bore of the cylinder. These gaskets, however, completely overcome this difficulty, as the packing-ring never adheres to them, but is always free 75 to expand the instant water is let into the cylinder, no matter how long the elevator may have remained unused. This form of my invention may be modified by casting the flange D with the follower F, instead of making it 80 part of the piston-head.

When the device is to be applied to elevators that operate with a pushing action, as seen in Fig. 3, the flange D is omitted from head C, and the latter is provided with a series of lugs 85 or stumps, J, into which are tapped the bolts E, that secure the follower to the piston, or said lugs may be cast with the follower; but in either case the head C must be perfectly watertight. The operation of this piston is essentially the same as the one seen in Fig. 1, the water now flowing between the lugs J and expanding the ring I, which latter moves freely because it is clamped between the two gaskets G H, and not between metallic surfaces. This 95 form of piston may be modified by placing the follower above the head, and suitably perforating the latter, so as to allow the water to circulate around the lugs or stumps.

In the modification shown in Fig. 5, the lugs 100 or stumps are omitted, and short tubes or washers are substituted therefor. This illus-

tration also shows the opposing surfaces of the head and follower chamfered off near their margins, so as to impart a wedge shape to the packing-ring, and thereby render the latter 5 more liable to expand with a very slight pressure of water or other medium.

Whichever form of my piston is adopted, care must be taken to arrange the gaskets G H in such a manner as to prevent their outward 10 expansion by the pressure of water or other fluid within the annular chamber of the piston. Such an expansion of gasket G is prevented by the bolts E, that pass through it, while any 15 distention of gasket H is guarded against by fitting it up tightly against the outer wall or face of the annular flange D of head C. This expansion of said gaskets is, however, prevented in many cases simply by the close adhesion 20 that naturally occurs when india-rubber is maintained in contact with metal for any length of time; but the packing-ring I is always 25 free to expand, because it is clamped between said gaskets, and is nowhere in contact with metal.

25 I am aware it is not new to make a water-packed pump-piston of three separate and distinct rings, all of which are capable of being expanded outwardly by the pressure of the fluid behind them, as this construction is seen 30 in Letters Patent No. 63,454, granted April 2, 1867, to M. J. Althouse; but as distinguished

from this piston, and all others of a similar character, it is the intermediate ring alone in my piston that is allowed to expand, while the two outer rings or gaskets are arranged especially to prevent such expansion. 35

I claim as my invention—

1. A water-packed piston consisting of an elastic non-metallic ring, I, clamped between two non-metallic gaskets, G H, which gaskets 40 are applied to the piston in such a manner as to prevent them being expanded outwardly, as herein described.

2. The combination of head C, bolts E, follower F, non-metallic gaskets G H, elastic non- 45 metallic packing-ring I, and stumps J, or the equivalents of said stumps, as and for the purpose specified.

3. The combination of perforated head C c, annular flange D d, follower F, non-metallic 50 gaskets G H, and non-metallic packing-ring I, the gasket G being retained in position by the same bolts, E, that secure the follower to the head, and the inner edge of gasket H being fitted up snugly against said flange D d, for 55 the purpose stated.

In testimony of which invention I hereunto set my hand.

WARREN WARNER.
